MECHANISM FOR CONTROLLING LOOM
STOP MOTIONSJoseph P. Costello, Philadelphia, Pa., assignor to
Collins & Aikman Corporation, Philadelphia,
Pa., a corporation of Delaware

Application May 2, 1933, Serial No. 669,039

10 Claims. (Cl. 139—340)

My invention is designed to provide means for controlling the operation of a loom or similar apparatus so that the loom is stopped after a predetermined number of picks, beats, or like operations. My improvements are particularly applicable to double plush looms to stop the loom upon the exhaustion of the yarn cops so as to avoid misweaving or wastage of yarn, or upon the production of a predetermined length of fabric.

10 My improvements provide means which may be synchronized with weft laying mechanism and operated when a sufficient number of picks of given width have been thrown to substantially exhaust the cops. The transmission of the controlling impulse to the loom stop motion may be transmitted through mechanical or electrical mechanism or both.

In the preferred embodiment of my improvements, there is provided a device such as a "dagger" normally tending to move into the path of a member of the loom, having a regular beat, such as a sword or feeler motion. The dagger or like device is operable by such loom member to permit the functioning of the usual loom stop motion, such as a switch or belt shifter.

Preferably the dagger mechanism tends normally to move into the path of the loom member, either by gravity or the action of a spring or weight, but is latched or held against such tendency by latching mechanism, which is normally movable by gravity or a spring into latching position. The latching mechanism may be rocked against its latching tendency through the action of a rocker or oscillating device controlled by a cam operable in synchronism with the beat of the loom; the rocking device acting through either an electrical train of parts, a mechanical train of parts, or both.

The characteristic features and advantages of my improvements will more fully appear from the following description and the accompanying drawings of an illustrative embodiment thereof.

In the drawings, Fig. 1 is a top plan view of a portion of the end of a loom having my improved mechanism applied thereto; Fig. 2 is a side elevation of the end of the loom shown in Fig. 1; Fig. 3 is a diagrammatic perspective view of detached parts illustrating the operation of my improved mechanism; Fig. 4 is a detail view of cam and rocker mechanism comprised in my improvements, and Fig. 5 is a detail side elevation of a worm and screw device for operating a cam employed in the loom mechanism.

In the form illustrated, my improvements are applied to a usual form of double shuttle plush

loom having a frame 1 to which is fixed a spring lever 2 connected with a usual stop motion, such as a belt shifter or electric switch (not shown) for disengaging power from the shaft 3, through which ordinary loom mechanisms are driven in the usual manner.

The upper part of the lever 2 is provided with a handle 4 by which it may be shifted in the frame slot 5 into and out of engagement in the notch 6 for holding the lever in the "go" position.

The lever may also be disengaged from the notch 6 to permit it to spring into the "off" position in the slot by an arm or bracket 7 pivotally connected with the frame 1. The bracket 7 is rocked to disengage the lever 2 from the notch 6 by a reciprocatory member of the loom, such for instance, as the lever 8 which is rocked by an arm or cam 9 on the shaft 3. The movement of the lever 8 may be transmitted to the bracket 7 through a dagger 10 carried by the shaft 11 journaled in bearings 12 of the bracket 7, and normally tending to move into the plane of the step or contact member 13 on the member 8.

The shaft 11 has fixed to the end thereof an arm or crank 14 connected, through the adjustable link 15, with an arm 16 pivotally connected with the frame by a pintle 17 and the arm or lever 16 is guided and its movement limited by a bracket 17' connected with the frame.

The lower part of the arm 16 is provided with a cam surface 18 for the engagement of an arm 19 on the oscillatory hub 20. When the hub 20 is turned so that the arm 19 engages the cam surface 18, the arm 16 acts through the link 15, arm 14 and shaft 11 to elevate the dagger 10 out of the path of the step 13. When the hub 20 is turned so that the arm 19 disengages the cam surface 18, the latter drops and permits the dagger 10 to fall into the path of the step 13 so that the arm 7 is rocked and the lever 2 disengaged from the notch 6, with resulting movement of the loom stop motion to stop the machine.

The hub 20 may be oscillated, after a desired number of picks have been thrown, either electrically or mechanically or both. The hub 20 has an arm 21 connected by a link 22 with one arm of a bell crank 23 fulcrumed on the frame. The other arm of the bell crank 23 is connected by a link 24 with an arm 25 containing a number of notches or holes for receiving the hooked end of the link 24. The arm 25 is fixed on an oscillatory shaft 26 having thereon the disk 27 having a cam periphery forming a projecting boss. A dog 28 coacting with a notch in the shaft 26

prevents excessive anti-clockwise movement of such shaft.

The disk 27 is movable in a clockwise direction by a knocker 29 pivoted on the pintle 30 and normally drawn in one direction by a spring 31. The knocker 29 has pivotally connected therewith a toe piece 32 for the engagement of the boss on the disk 27, the point 34 of such toe piece being normally drawn outwardly by the spring 33 to engage the boss on the disk 27 upon movement of the knocker 29 in one direction. A stop (not shown) limits the outward movement of the point of the toe piece, which is permitted to move inward by the expansion of the spring 33 when the knocker 29 is moved toward the left (Fig. 4).

The knocker 29 is moved toward the left against the tension of the spring 31 by a roller or cam 35 fixed on the shaft 36 and rotated in a clockwise direction in synchronism with the operation of the loom. When the high point of the cam 35 passes its point of engagement with the knocker 29, the latter is drawn quickly toward the right (Fig. 4) by the spring 31 and the point 34 momentarily engages and rocks the boss on the periphery of the cam disk 27.

The length of the periphery of the cam 35 is so proportioned to the length of yarn on the bobbin and the width of the fabric being woven that the high point of the cam 35 releases the knocker 29 when the yarn on the bobbin has been exhausted to the desired extent and consequently the parts 28, 26, 25, 24, 23, 22, 21, 20, 19, 18, 16, 15, 14, 11 and 10 are rocked to effect the stopping of the machine when the shuttles are in their boxes on the right side of the loom and the cops on the bobbins substantially exhausted.

To supplement or supersede the effect of the blow of the knocker 29 upon the member 27, an electric circuit may be provided containing a source of electricity 37, an electro-magnetic coil 38, and suitable conductors 39 and 40. The circuit may be controlled by the cam 35, as, for instance, by connecting the conductor 39 with the conducting toe piece 32 and connecting the conductor 40 with an insulated contact 40' with which the toe 34 momentarily engages at the limit of its movement to the right (Fig. 4). The closing of the circuit causes the electromagnetic coil 38 to actuate its armature 41, which through the link 42, bell crank 43, link 44 and arm 44' oscillates the hub 20 on its pivot to move the arm 19 out from under the cam 18.

The cam 35 is rotated in desired synchronism with the operation of the shuttle mechanism or beat of the loom by a worm wheel 45 meshing with a worm 46 on the shaft 47. The shaft 47 has fixed to the lower end thereof a worm wheel 48 meshing with the worm 49 fixed to the shaft 50 by the pawl 51 which is pivoted on the hub 46' of the worm 49 which is driven from the shaft 3 through suitable gearing. The ratchet 50' being integral with the hub 46' of the worm 49 turns with it and the pawl 53' pivoted on a fixed portion of the loom rides idly over it when the loom is weaving forwardly. A collar 52' fixed to the shaft 50 by a set screw limits axial movement of the worm and ratchet. When the loom is reversed for picking out or unweaving, pawl 51' will disengage from shaft 50 and ride over it, whereas pawl 53' will engage the teeth 55' of the ratchet 50' and prevent the worm from turning, thereby maintaining the synchronism of the measuring cam and the length of weft on the bobbin, regardless of the amount of picking out or unweaving.

The gear mechanism by which motion is transmitted to the cam disk 35 is so proportioned that the cam disk is rotated once during the number of reciprocations of the shuttles necessary to exhaust the yarn on the bobbins. By suitable adjustments of gear ratios, the operation of the stop mechanism may be varied to accord with variations in the yardage of yarn on the bobbin and the width of fabric being woven therefrom.

In the operations of a loom equipped with my improvements, the yardage placed on the bobbins will be so proportioned to the width of the fabric being woven that the yarn will be exhausted after a number of picks taking place in the time required for one revolution of the cam disk 35, or the gear ratios may be adjusted to give the number of picks required to exhaust the yarn on the bobbin during a revolution of the cam disk 35.

When the loom is started with a freshly filled bobbin, the lowest part of the cam 35 abuts against the knocker 29. The cam 35 is rotated slightly with each beat of the loom and presses the knocker 29 outwardly against the action of the spring 31, which is thereby placed under tension. When the toe 32 engages the cam member 27 in the outward movement of the knocker 29, the toe rocks against the action of the spring 33 to pass the point of the member 27, the spring acting to restore the toe 32 to its normal position as soon as it has passed the high point of the member 27.

When the highest point of the cam disk 35 passes the bearing surface of the knocker 29, the latter is rapidly pulled in by the spring 31 and the toe 32 knocks the member 27 and rocks the shaft 26, arm 25, link 24, bell crank 23, link 22 and arm 21 to turn the hub 20 on its axis. Simultaneously with this mechanical actuation of the hub, the knocker closes the circuit containing the conductors 39 and 40 and the coil 38 of the electromagnet is excited to actuate the armature 41 which lifts the link 42 and, through the bell crank 43 and link 44 and arm 44', also tends to rock the hub 20 on its pivot.

The rocking of the hub moves the arm 19 from under the cam 18 of the lever 16 thereby permitting the descent of the link 15, the rocking of the shaft 14 and the movement of the dagger 10 into the path of the step 13. The reciprocation of the latter brings it into contact with the dagger 10 and rocks the arm 7 on its pivot to disengage the lever 2 from its notch 6 and permit the spring portion of the lever to shift it in the slot 5 and, through the usual loom stop motion, such as a switch or belt shifter, to the "off" position.

As soon as the mechanism has been actuated as above described, the weight of the arm 25 and its connected parts, or supplemental weight attached thereto, restores the members to their original positions, so that when the lever 2 is manually shifted to "go" position and engaged in its notch 6, the stop control mechanism is again ready to function upon the exhaustion of the yarn on a new bobbin.

Having described my invention, I claim:

1. Mechanism for controlling a loom stop motion which comprises a knocker having a toe member pivotally connected therewith, means for giving a snap action to said knocker, an oscillatory device, mechanism through which said toe member oscillates said device, a dagger, and means whereby said oscillatory device operates said dagger.

2. In apparatus for controlling a loom stop motion just before or upon the exhaustion of a weft supply package, the combination with a cam having an abrupt step, of a knock-off device normally biased in one direction and movable in the opposite direction by the portion of said cam between the foot and head of said step, and means for moving said cam during the laying of a yarn package a distance sufficient to drop said knocker from the head to the foot of said step and including a worm gear preventing reversal of the movement of said cam.
3. In an apparatus for controlling a loom stop motion just before or upon the exhaustion of the weft supply package, the combination of a rotatable member having a cam track with an abrupt step, a knock-off device normally biased in one direction and moved by the portion of the cam between the foot and head of said step in the opposite direction, said knock-off device being snapped in its biased direction upon passing over the head of said step, and means for rotating said cam at a rate proportional to a length of yarn in a package and comprising a one way clutch driven in one direction by a loom member and driving in one direction a worm gear through which motion is imparted to said first named rotatable member in one direction only.
4. In apparatus for controlling the stop motion of a loom just before or upon the exhaustion of a weft supply package, the combination of a knock-off device normally biased in one direction and having a contact member yieldable in one direction only, an oscillatory member in the path of said contact member and rocked thereby during the movement of said knock-off device in its biased direction, and means for moving said knock-off device contra to its biased direction, said contact member yielding to pass said oscillatory member upon the movement of said knock-off device by said means.
5. In a loom having a weft supply package containing a measured length of weft, mechanism for controlling a loom stop motion which comprises a rotatable cam operable in synchronism with the loom mechanism during forward weaving, means for rotating said cam during the running of the loom for weaving and means for latching the rotation effecting means in inoperative position during unweaving to maintain the synchronism between the measured length of weft, regardless of pick outs or unweaving before exhaustion of the weft package.
6. In a loom having a weft supply package, mechanism for controlling a loom stop motion just before or upon the exhaustion of the weft supply package which comprises a loom member, a dagger movable into and out of the path of the loom member, means for oscillating said dagger comprising an arm having a cam there-

on, an oscillatory device movable into and out of engagement with said cam, and means for oscillating said oscillatory device and tending to bias it normally to position for holding said cam in position to hold said dagger out of the path of said loom member, and a cam for oscillating said member against the action of said means last named.

7. In a loom having a weft supply package mechanism for controlling a loom stop motion just before or upon the exhaustion of the weft supply package which comprises a loom member, a dagger movable into and out of the path of the loom member, means for oscillating said dagger comprising an arm having a cam thereon, an oscillatory device movable into and out of engagement with said cam, and means for oscillating said oscillatory device and tending to bias it normally to position for holding said cam in position to hold said dagger out of the path of said loom member, and a weft measuring cam for oscillating said member against the action of said means last named.

8. Mechanism for controlling a loom stop motion which comprises a loom member, a dagger movable into and out of the path of said loom member, and means controlling said dagger and comprising an oscillatory member, a cam operable oscillating arm, a measuring device comprising a cam for operating said second named member, means for rotating said cam once during a predetermined number of movements of said loom member first named, a circuit controlled by said cam and a link and lever mechanism operable by said oscillatory member.

9. In a loom having a shuttle mechanism, means for controlling a loom stop motion comprising a rotatable cam operable in synchronism with the loom shuttle mechanism, a knocker operable by said cam and having a pivotally connected toe, a spring giving a snap action to said knocker after operations of said knocker by said cam, an oscillatory member, mechanism through which said toe oscillates, said oscillatory member, a dagger, and means whereby said oscillatory member operates said dagger.

10. In apparatus for controlling a loom stop motion just before or upon the exhaustion of a weft supply package, the combination with a cam having an abrupt step, of a knock-off device normally biased in one direction and movable in the opposite direction by the portion of said cam between the foot and head of said step, and means for moving said cam during the laying of a yarn package a distance sufficient to drop said knocker from the head to the foot of said step and including means preventing reversal of the movement of said cam when the loom is reversed.

JOSEPH P. COSTELLO. 60
